UNITED STATES PATENT OFFICE.

BENJAMIN STUART PASCHALL, OF SEATTLE, WASHINGTON.

MECHANISM FOR MASSAGING.

Application filed August 9, 1921. Serial No. 490,852.

To all whom it may concern:

Be it known that I, BENJAMIN STUART PASCHALL, a citizen of the United States, residing at Seattle, in the county of King 5 and State of Washington, have invented a certain new and useful Mechanism for Massaging, of which the following is a specification.

My invention relates to mechanism 10 for giving massage. More particularly, my invention relates to a machine which moves two or more rubber applicators having projections, or other suitable contact members, for various parts of the 15 surface of the body in such a way that while most closely imitating qualitatively the various movements and effects which may be produced when massage is given by manual application, yet quantitatively greatly im- 20 proving upon said manual application.

The beneficent effects of massage treatment for certain conditions and ills, pathologically considered, are well recognized. However, such treatment must be regular 25 and frequently repeated throughout a relatively long period of time for its benefits to be developed, and such treatment must be performed accurately to be beneficial, to omit all reference to the great danger of 30 positive injury if not so performed. As heretofore commonly administered, such treatment is almost exclusively rendered manually. Such conditions combine to 35 make such treatment so expensive that its benefits are not available to the great per- cent of those needing such treatment.

As aids to massage treatment, devices heretofore have been designed for massaging various portions of the body by oscillations 40 of a fluid or by vibratory movements in circles of a single applicator. Such devices fail to provide for the essential movements which characterize the art of massaging, viz, the alternate stretching and pinching 45 together of the parts engaged so as to pick up the same, as it were, while simultaneously being subjected to an up and down motion which imparts an increasing and decreasing 50 pressure to the parts being treated, the said movements being those which a masseur attempts to obtain by hand.

The principles upon which massage is based are those which have to do with the 55 artificial production of physiological changes in the tissues and structures to

which the art is applied. Massage is artificial exercise and is applicable to those conditions in which natural exercise is inadequate, unsatisfactory or impossible. Its purpose is to squeeze and work out of the 60 tissues the poisonous metabolic products and to bring to the treated part a flood of fresh material, or to treat the various tissues and structures of the body so as to restore or keep up the normal nutrition of the parts 65 to which this art is applied, or even in some instances to artificially greatly increase it. This is accomplished by means of certain rubbing, rotating, squeezing, stretching and kneading movements performed in such a 70 manner that the circulation is increased, fresh nourishment brought to the part so treated and effete products carried away. The wasting or degeneration of the structure is thus prevented, or where wasting and 75 atrophy have already occurred, by means of this art a normal condition of circulation may be restored. Applied to the treatment of the scalp for baldness for instance; it is well known that loss of the hair takes 80 place gradually as the arterial circulation becomes restricted and dies out by slow degrees from a thinning of the scalp itself which results in its subsequent contraction over the skull with the tightness of a drum 85 head. The nutrition to each little hair follicle is thus slowly cut off and the individual hair itself becomes thinner and thinner and more irregular in its structure from this restricted circulation, until it finally becomes so atrophied and reduced in size that it merely remains as a short colorless fuzz before final and complete baldness results. It has been frequently demonstrated that 90 careful and painstaking massage with the fingers carried over many months or sometimes years will restore the circulation to a normal condition and following this the hair will grow again as it was in the first place, and this is known to take place as 95 long as there is this minute fuzz-like hair projecting from the hair follicle.

Furthermore, the examination of the shaft of a hair under the microscope, particularly in women, where it is breaking after attaining short lengths will show certain marked irregularities in the shaft of the structure itself, (constrictions) due to disturbances in its nutrition during the growth period which 100 may be entirely corrected by measures which 110

will fully restore the circulation and nutrition of the scalp. The machine herein described, which embodies my invention, accomplishes this end very efficiently and completely.

Baldness or thinning of the hair is entirely due to mechanical causes and not to some parasitic disease, except in a very small percentage of cases. The top of the head is the highest portion of the body and it is here consequently that the blood pressure is the least. In addition to this when baldness takes place it always begins at those parts of the scalp which are the most terminal of the end branches of the tiny arteries, and baldness almost never becomes so complete as to be observed in that portion of the scalp where the large arteries exist, since here the thinning process cannot take place. That is, it never becomes complete because the circulation on the side of the head is always adequate. In those cases where disease has caused thinning or falling of the hair the sides of the head suffer as well as the top since a disease process can effect one part of the scalp as well as another. Falling of the hair in men is more frequent and marked than in women for two reasons,—the stiff hat and the natural greater thinness of the scalp in males. The stiff hat starts the cutting off of the circulation and this first reduction in blood supply starts what is known in medicine as a pernicious circle. A reduction of blood supply causes contraction of the scalp tissue, and contraction of this tissue causes further reduction of blood supply so that each in turn makes the other worse until or unless it is checked, and a condition of health restored by artificially increasing the blood supply once more, as the herein described machine is claimed to do. The scalp of women is naturally slightly thicker than in men so there is less complete baldness, but there are as many if not more annoying conditions as far as they are concerned, due to the irregular growth of the hair shaft when the circulation is imperfect, so that the hair keeps breaking off as fast as it becomes a few inches in length. The herein described machine has been devised for the successful treatment of the long hair of women as well as the short hair of men.

All hair tonics and restoratives contain certain irritable substances whose object is to increase the redness or hyperæmia of the scalp but their effect is not sufficient to reach the deeper layers of the scalp so as to have any beneficial effect, and reference to any treatise on anatomy will show that the arteries supplying the scalp are to be found in the subcutaneous areolar tissue between the scalp layer and the bony portion of the skull. Thus as time goes on, where the skin layers covering the skull begin to contract

and tighten, as happens whenever skin is poorly nourished, this tightening down process inevitably further cuts off the small arteries which are lying between it and the skull. This results as already stated in a further restriction of nutrition to the scalp layer whereupon it contracts still more and thus a pernicious circle is set up which slowly results in baldness. The machine which I have devised is applicable to all of these cases in that it is so constructed as to actually lift the scalp, loosen it and stretch it as well as causing a temporary increase in circulation so that the little dying arteries have a chance to expand and grow once more and in this way the scalp has restored to it the nourishment which was being cut off. A loose, thick scalp is almost always healthy. The thickness of the skin when the head has become entirely bald is less than one-fourth of that which is well surmounted with hair.

The primary object of my invention is to provide a massaging machine which will impart the movement which characterizes manual massage, viz, the rotary movement which results in the alternate stretching and pinching together of the parts being treated so that the same are picked up, as it were, while simultaneously being subjected to an up and down motion which imparts an increasing and decreasing pressure as the applicators move in and out. Another primary object of my invention is to provide a massaging machine in which practically all the contacting surface of the applicators is free to make a relatively fixed engagement with the surface being treated while contacting with the same, being particularly adapted to grasp and hold firmly the skin of the hairy portions of the head without becoming entangled with the hair. Finally, a primary object of my invention is to provide such a massaging device which is simple in construction and economical to manufacture.

The above mentioned general objects of my invention, together with others inherent in the same, are attained by the mechanism illustrated in the following drawings, the same being merely preferred exemplary forms of embodiment of my invention, throughout which drawings like reference numerals indicate like parts.

Figure 1 is a plan view of a device embodying my invention showing the worm with its right and left-handed threads in engagement with the gears.

Fig. 2 is a view in section on broken line 2, 2 of Fig. 1;

Fig. 3 is a view in perspective of an applicator in conjunction with its spindle, the applicator being shown in two positions to show the degree of angular movement preferably permitted the applicator with respect to the longitudinal axis of the spindle;

Fig. 4 is a view of the bottom portion or contacting surface of one form of the applicator;

Fig. 5 is a diagrammatic plan view illustrating the mounting and relative positions of the spindles when four are employed—the same being shown when the applicators are farthest apart;

Fig. 6 is a diagrammatic view illustrating the mounting and relative position of the spindles when the same are rotated through an angle of 135° from the position shown in Fig. 5;

Fig. 7 is a diagrammatic view illustrating the mounting and relative position of the spindles when the same are rotated through an angle of 45° from the position shown in Fig. 6;

Fig. 8 is a diagrammatic view illustrating the mounting and relative position of the spindles when the same are rotated through an angle of 45° from the position shown in Fig. 7;

Fig. 9 is a view of a modified form of a device embodying my invention as respects the actuating means;

Fig. 10 is a view of still another modified form of a device embodying my invention as respects the actuating means;

Fig. 11 is a view of a modified form of spindle embodying my invention; and

Fig. 12 is a view of a modified form of actuating means adapted to have the motor mounted on top of the massaging device.

An applicator 13 of rubber or the like (these may be of circular or other form) is pressed upon a spindle holding member 14, composed of a spindle shank 15 and the grooved drum 16. The said spindle shank 15 is preferably provided with a ball 17 and a socket 18, connector means for said applicator. The upper end of said spindle shank 15 is preferably provided with a groove 19 into which a ball 20 is pressed by a spring 21 in the recess 22 of the crank shaft eccentric 23. Gear 24 has keyed upon it the crank shaft eccentric or disk 23. Provision is made in the device illustrated for three other such spindle holding members, namely 25, 26, and 27, all of which are similar in construction, and all of which are in reality crank pins eccentrically placed with respect to the disks 23, which latter rotate about their respective centers of movement.

These spindle-holding members 14, 25, 26 and 27 have gears 28, 29, and 30 respectively, all of which are also similar in construction to gear 24. Gears 24 and 28 mesh with the worm 31 on shaft 32 while gears 29 and 30 mesh with worm 33. Bearings 34 and 35 are provided for the shaft 32. A housing, consisting of a base plate 36 and a covering plate 37 form a housing for said gears and worms, the same being held together by countersunk screws 38.

In the modified form shown in Fig. 9 the gears 24, 28, 29 and 30 intermesh with each other and are actuated by a gear 39 which intermeshes only with gear 24. By gearing in this manner, substantially the same motion may be imparted to the spindles as is done by the worms 31 and 33.

In the modified form shown in Fig. 10, the gears 24, 28, 29 and 30 do not intermesh with each other but intermesh with a single gear 40. This form does not impart the same motion to the spindles as obtained by the preferred forms heretofore described, but cause them to follow one another in their movements successively as opposed to simultaneously cooperating by approaching each other and by moving apart.

In the modified form shown in Fig. 11, a spindle having two ball sections 41 and 42 is mounted with a bearing 43 intermediate the applicator 13 and the crank-shaft eccentric 23.

In the modified form of the actuating means shown in Fig. 12, provision is made for mounting the motor on top of the cover plate 37 so that its weight may be utilized in supplying pressure to the device. A shaft 44 is mounted in bearings 45 and 46—said shaft having a worm 47 which meshes with worm 48 provided on shaft 32. Bevel gears 49 on shaft 44 engage a worm 50 on the motor drive-shaft 51.

The mode of operation of my device is as follows: The shaft 32 is caused to revolve, preferably by a pedal-controlled electric motor, and since the worms 31 and 33 are oppositely directed, gears 24 and 28 revolve in opposite directions to each other, as also do gears 29 and 30. This preferable arrangement results in each gear moving in the opposite direction to the adjacent gear.

The crank-shaft eccentrics 23 are keyed to the said gears 24, 28, 29 and 30. The said eccentrics hold the spindle-holding members preferably in the positions illustrated in Fig. 5. From these positions it is manifest that any movement of the gears will cause the side spindle-holding members 14 and 23 to first approach each other, as do also the side spindle-holding members 25 and 27, and then the said two side pairs together approach each other. Thus is effected the final step of the "pinching up" movement. After the spindle-holding members reach their closest together position as respects the center 52, as shown in Fig. 7, the two side spindle-holding members 14 and 26 move apart, as do also the side spindle-holding members 25 and 27. This causes spindle-holding members 26 and 27 to approach each other, and likewise spindle-holding members 14 and 25. Then all the spindle-holding members next move apart in assuming their farthest apart position as shown in Fig. 5. Thus is effected the "stretching out"

movement. In assuming these farthest apart and closest together positions and the intermediate positions illustrated, the gears are caused to move; first, 135° (from position shown in Fig. 5 to that in Fig. 6); second, 45° (from position shown in Fig. 6 to that in Fig. 7); and third, 45° (from position shown in Fig. 7 to that in Fig. 8).

The spindle-holding members 14 are 10 revolvably mounted in the crank-shaft eccentrics 23 so that said spindles need not turn upon their own axis and in this wise all danger is avoided of the hair becoming broken or entangled about the spindle-holding member when said massaging device is applied to the scalp.

The ball 17 and socket 18, connector means, renders the applicator 13 free to make contact with the part to be massaged 20 throughout the entire engaging surface of said applicator.

In addition to the pinching together and stretching movements, the eccentrical mounting of the applicators gives them an up and 25 down movement when applied to a curved or spherical surface such as the scalp. This can be readily shown by placing a spherical body on the applicators and then cause the applicators to be actuated. The sphere will 30 move up and down.

A plurality of the units composed of the applicator, spindle-holding-members, and crank-shaft eccentric, or multiples of two or 35 four of these units arranged to work together as illustrated in the preferred form, could be used with advantage for bodily massage since the four applicators working toward and away from one another with a ball socket within the rubber part itself, so 40 that they may fit any part of the body to which they are applied, fulfill all the requirements for giving mechanical massage to such a degree that it is equal if not superior to manual applications.

45 Obviously, changes may be made in the form, dimensions, and arrangement of the parts of my invention, without departing from the principle thereof, the above setting forth only preferred forms of embodiment.

50 I claim:

1. A device of the character described including a plurality of applicators each movable bodily about an endless path, and means for operating said applicators to cause them 55 to move in unison, and alternately towards and from every applicator in succession.

2. A massaging device including a plurality of applicators each movable bodily about a center of movement, and means for imparting similar and relative movement to the several applicators to cause each applicator to approach toward and recede from each of the remaining applicators in succession.

60 3. A massaging device including a plurality of applicators each movable bodily

through a closed path which is concentric with its center of movement, and operating means including eccentrics rotatable about the several centers of movement for causing the respective applicators to move bodily 70 toward and away from each other during rotation of the said eccentrics.

4. A device of the character described embodying a plurality of applicators, a spindle-holding-member for each of said applicators, a crank-shaft eccentric to impart a rotary motion as respects the axis of said eccentric to each of said spindles, said eccentric having a socket and spring and ball snap which extends into a groove in said spindle whereby said spindle may turn in said socket without rotating upon its own axis, and means to actuate said eccentric.

5. A device of the character described embodying a plurality of applicators, a spindle-holding-member for each of said applicators, said spindle having flexible means connecting to itself said applicators whereby the contacting surface of said applicator is free to make a relatively fixed engagement with the surface being treated while contacting with said surface, a crank-shaft eccentric to actuate each of said spindles, and means to actuate said eccentric.

6. A device of the character described embodying a plurality of applicators, a spindle-holding-means for each of said applicators, said spindle having a ball and socket connector means for the applicator whereby the entire contacting surface of said applicator is free to make a relatively fixed engagement with the surface being treated while contacting with said surface, a crank-shaft eccentric to actuate each of said spindles, and means to actuate said crank-shaft eccentric.

7. A device of the character described embodying a plurality of applicators, a spindle-holding-member for each of said applicators, said spindle having a ball and socket connector means with said applicator whereby the entire contacting surface of said applicator is free to make a relatively fixed engagement with the surface being treated while contacting with said surface, a crank-shaft eccentric to impart a rotary motion as respects the axis of said eccentric to each of said spindles, said eccentric having a socket and spring and ball snap which extends into a groove in said spindle whereby said spindle may turn in said socket without rotating upon its own axis, and means to actuate said crank-shaft eccentric.

8. A massaging device including a plurality of applicators each bodily movable in a closed path about its individual center of movement, the several centers of movement being relatively fixed, and means for moving each applicator through its path 125 with like eccentricity to the respective cen-

ters of movement and with each applicator at all times varying in its eccentric position from every other applicator.

9. In combination with a device of the character described, a spindle-holding-member for an applicator, said spindle having means on one end whereby it may be releasably engaged and may be rotatively held without turning upon its own axis, and on 10 the other end of said spindle a ball and socket connector means for said applicator.

10. A device of the character described embodying a plurality of applicators, a spindle-holding-member for each of said applicators, said spindle having a ball and socket connector means with said applicator whereby the entire contacting surface of said applicator is free to make a relatively fixed engagement with the surface being treated 20 while contacting with said surface, a crank-shaft eccentric to impart a rotary motion as respects the axis of said eccentric to each of said spindles, said eccentric having a socket and spring and ball snap which extends into 25 a groove in said spindle whereby said spindle may turn in said socket without rotating upon its own axis, a gear mounted upon each of said eccentrics, and a worm to actuate said gears.

30 11. A device of the character described embodying two applicators, a spindle-holding-member for each of said applicators, a crank-shaft eccentric to impart a rotary motion as respects the axis of said eccentric to 35 each of said spindles, said spindles being mounted in the crank-shaft eccentrics in opposite phase, whereby said applicators are alternately and simultaneously moved towards and away from each other.

40 12. A device of the character described embodying three applicators, a spindle-holding-member for each of said applicators, a crank-shaft eccentric to impart a rotary motion as respects the axis of said eccentric to 45 each of said spindles, said spindles being mounted in said eccentrics in triangular position, two of said spindles being mounted in the crank-shaft eccentric to turn in the same direction while the third spindle turns 50 in the opposite direction to said first named spindles, whereby said three applicators are alternately and simultaneously moved towards and away from each other.

55 13. A device of the character described embodying four applicators, a spindle-holding-member for each of said applicators, a crank-shaft eccentric to impart a rotary motion as respects the axis of said eccentric to each of said spindles, said spindles being 60 mounted in the crank-shaft eccentric equidistantly with respect to each other—that is, in the form of a square—and said spindles maintaining said square formation while rotating, said square increasing and decreasing 65 during said rotation whereby the ap-

plicators are caused to be alternately and simultaneously moved towards and away from each other.

14. A device of the character described embodying a plurality of applicators, a 70 spindle-holding-member for each of said applicators, a crank-shaft eccentric to impart a rotary motion as respects the axis of said eccentric to each of said spindles, said spindles being mounted in the crank-shaft eccentric 75 eccentric with equidistant spaces between each adjacent pair of spindles, each two adjacent pairs forming a square and said spindles maintaining said square formation while rotating, said square increasing and 80 decreasing during said rotation whereby the applicators, as respects any adjacent four, are caused to be alternately and simultaneously moved towards and away from each other.

15. A device of the character described embodying four applicators, a spindle-holding-member for each of said applicators, a 90 crank-shaft eccentric to impart a rotary motion as respects the axis of said eccentric to each of said spindles, said spindles being mounted in the crank-shaft eccentric in opposite phase to each other, whereby said applicators are alternately and simultaneously 95 moved towards and away from each other.

16. A device of the character described embodying two applicators, a spindle-holding-member for each of said applicators, said spindle having a ball and socket connecting means with said applicator whereby the entire contacting surface of said applicator is free to make a relatively fixed engagement with the surface being treated 100 while contacting with said surface, a crank-shaft eccentric to impart a rotary motion as respects the axis of said eccentric to each of said spindles, said eccentric having a socket and spring and ball snap which extends into a groove in said spindle whereby 105 said spindle may turn in said socket without rotating on its own axis, and said spindle being mounted in the crank-shaft eccentrics in opposite phase whereby said applicators are alternately and simultaneously 110 moved towards and away from each other.

17. A device of the character described embodying three applicators, a spindle-holding-member for each of said applicators, said spindle having a ball and socket connecting means with said applicator whereby the entire contacting surface of said applicator is free to make a relatively fixed engagement with the surface being treated 120 while contacting with said surface, a crank-shaft eccentric to impart a rotary motion as respects the axis of said eccentric to each of said spindles, said eccentric having a socket and spring and ball snap which extends into a groove in said spindle whereby said 125 spindle may turn in said socket without rotating 130

- on its own axis, and said spindles being mounted in said eccentrics in triangular position, two of said spindles being mounted in the crank-shaft eccentric to turn in the same direction while the third spindle turns in the opposite direction to said first named spindles, whereby said three applicators are alternately and simultaneously moved towards and away from each other.
18. A device of the character described embodying four applicators, a spindle-holding-member for each of said applicators, said spindle having a ball and socket connecting means with said applicator whereby the entire contacting surface of said applicator is free to make a relatively fixed engagement with the surface being treated while contacting with said surface, a crank-shaft eccentric to impart a rotary motion as respects the axis of said eccentric to each of said spindles, said eccentric having a socket and spring and ball snap which extends into a groove in said spindle whereby said spindle may turn in said socket without rotating on its own axis, and said spindles being mounted in the crank-shaft eccentric with equidistant spaces between each adjacent pair of spindles, each two adjacent pairs forming a square and said spindles maintaining said square formation while rotating, said square increasing and decreasing during said rotation whereby the applicators, as respects any adjacent four, are caused to be alternately and simultaneously moved towards and away from each other.
19. A device of the character described embodying four applicators, a spindle-holding-member for each of said applicators, said spindle having a ball and socket connecting means with said applicator whereby the entire contacting surface of said applicator is free to make a relatively fixed engagement with the surface being treated while contacting with said surface, a crank-shaft eccentric to impart a rotary motion as respects the axis of said eccentric to each of said spindles, said eccentric having a socket and spring and ball snap which extends into a groove in said spindle whereby said spindle may turn in said socket without rotating on its own axis, and said spindles being mounted in the crank-shaft eccentric with equidistant spaces between each adjacent pair of spindles, each two adjacent pairs forming a square and said spindles maintaining said square formation while rotating, said square increasing and decreasing during said rotation whereby the applicators, as respects any adjacent four, are caused to be alternately and simultaneously moved towards and away from each other.
20. In a device of the character described, a plurality of applicators each bodily movable about its individual axis, said axes being grouped about a central point, and means for giving said applicators movements each in its respective path, which movements are angularly synchronized as respects said central point and are in opposite angular direction in successive applicators of the series.
21. In a device of the class described, a plurality of applicators each circularly movable about its individual axis, and grouped about a common point, and means for bodily moving each applicator about its individual axis to cause each one to approach towards and recede from each of the other applicators in succession.
- In witness whereof, I hereunto subscribe my name this 26th day of July, A. D., 1921.
- BENJAMIN STUART PASCHALL.
